DISPLAY CARD HOLDER

James E. Gibson, Jr., High Point, N. C.

Application July 13, 1954, Serial No. 31,406

Term of patent 7 years

(Cl. D80—5)

T-1

To all whom it may concern:

Be it known that I, James E. Gibson, Jr., a citizen of the United States of America, residing at High Point, county of Guilford, and State of North Carolina, have invented a new, original, and ornamental Design for a Display Card Holder, of which the following is a specification, reference being had to the accompanying drawing, forming a part thereof:

Figure 1 is a front elevational view of a display card holder embodying my new design;

Figure 2 is a side elevational view thereof;

Fig. 3 is a rear elevational view of the same, and

Figure 4 is a reduced rear elevational view with the rear folding flap in raised position.

I claim:

The ornamental design for a display card holder, as shown.
